UNITED STATES PATENT OFFICE.

HENRY H. HERRMANN, OF CHICAGO, ILLINOIS.

AIR-COMPRESSOR.

No. 844,724.

Specification of Letters Patent.

Patented Feb. 19, 1907.

Application filed August 7, 1905. Serial No. 273,032.

To all whom it may concern:

Be it known that I, HENRY H. HERRMANN, a citizen of the United States, residing at Chicago, in the county of Cook and State of Illinois, have invented a new and useful Improvement in Air-Compressors, of which the following is a specification.

My object is to provide an air-compressor of simple construction which shall adapt it for use in households and other places where power is not readily obtainable for compressing air for supplying household gas-making machines, for blowing-forces, and for other purposes.

My invention is illustrated in the accompanying drawings, in which—

Figure 1 is a partly-broken view, in sectional side elevation, of my improved air-compressor; Fig. 2, a section taken at the line 2 on Fig. 1 and viewed in the direction of the arrow; Fig. 3, an enlarged perspective view of one of the check-valves employed; and Fig. 4 a similar view of the several parts of the check-valve, illustrating them in their relative positions for assembling.

A is a receptacle or chamber of any suitable shape for the compressed air, that shown being rectangular in cross-section, supported on legs A', suitably braced, the receptacle having at one end an outlet a and in its sides inwardly-opening check-valves A², communicating with bellows B or other suitable construction of air-pump secured on the sides of the receptacle and each provided with an inwardly-opening check-valve B' of the same construction as the check-valves A², the form of pumps shown being the ordinary form of bellows, of which there may be one or more, it being preferred that each side of the receptacle when rectangular, as shown, be provided with a bellows.

Each check-valve is provided with an annular flange or valve-guide a' about one of its ends, against which a flexible valve a² abuts. The valve is held in place centrally of the guide by a screw a³, passing through the valve and into a support a⁴, mounted centrally of the guide in a cross-piece a⁵.

C is an elastic diaphragm secured at its edges to the inside surface of the receptacle, near the inner end thereof, to adapt it to be expanded, as shown by dotted lines in Fig. 1, to regulate the pressure of discharge from the receptacle, more particularly when the pres-

sure therein is rendered excessive by winding up the bellows-actuating mechanism, hereinafter described.

Journalized at one end of the receptacle in a frame D is a drive-shaft E, carrying near its center a windlass e, having wound upon it a rope or cable F, and on opposite sides of the windlass gears e' and e². The gear e' is loosely mounted on the drive-shaft and carries a pallet e³, which engages a ratchet-wheel e⁴, secured to the shaft, to rotate the gear e' when the shaft is turned by a crank-handle E', provided thereon, during the winding of the cable upon the windlass. The gear e² is fastened to the shaft to rotate therewith.

Journalized in the frame and in the end of the receptacle is a drive-shaft G, carrying a large gear g, fastened thereon and meshing with the gear e'. Meshing with the gear e² is a gear g', loosely mounted on the shaft G and carrying a pallet g², which engages a ratchet-wheel g³, secured to the shaft G, to turn it as the cable unwinds from the windlass. A gear g⁴, fastened to the shaft G, meshes with gears H H H H, one for each bellows, provided on shafts h, journalized in brackets h', each of which gears is connected to its respective bellows by a pitman-rod h², pivoted at one end on its respective gear and pivoted at its opposite end to a connecting-link h³, which is in turn pivotally connected with an arm h⁴, projecting from the bellows. Thus the turning of the gears will cause the bellows to be actuated to force air through the check-valves into the receptacle.

Suspended from a support I, with which the upper end of the cable F is connected, is pulley-and-weight mechanism for actuating the gears, comprising a fixed pulley K and a movable pulley K', the latter having suspended on it a weight K². The cable passes over the fixed pulley, under the movable pulley, and is secured at its free end to the support. Thus the descent of the weight causes the cable to unwind from the windlass and rotate the gears, as will be hereinafter explained. It is obvious that K and K' may each denote a series of pulleys in any desired number, and thus the machine be made to operate for a longer time during the unwinding of the cable from the windlass than where but two pulleys are employed, as shown.

The operation of the machine is as follows:

The cable is wound upon the windlass by rotating the drive-shaft by means of the crank-handle, bringing the weight to the position shown in Fig. 1. Upon releasing the handle 5 the weight descends, unwinding the cable from the windlass and turning the drive-shaft, which through its gear connection with the shaft G causes it to turn, and with it its gear g^4 , thereby rotating each of the gears 10 H to operate the bellows by their connections therewith. The bellows continue in operation until the pressure of the air in the receptacle is equal to the pressure attained in the bellows. When this degree of pressure is 15 attained, whether by shutting off the outlet from the receptacle or otherwise, the weight is interrupted in its downward movement until the pressure in the receptacle decreases, when the weight resumes its descent. Thus 20 the machine is automatic in its action and continues in either constant or interrupted movement until the cable is entirely unwound from the windlass. During the rewinding of the cable on the windlass it is desirable to continue 25 uninterrupted the operation of the bellows, and this is accomplished in the following manner: Upon operating the handle E' the pallet on the gear e' engages the ratchet-wheel e^4 , thus actuating the gear e' and the 30 gear g and causing the gear g^4 to turn in a direction opposite to that in which it turns during the unwinding of the cable. By turning the drive-shaft in the direction for winding the cable the gear g^4 on the shaft G is freely 35 rotated independently of the shaft as its pallet rides freely over the teeth of the ratchet-wheel g^3 .

The diaphragm C serves to render uniform the pressure in the receptacle when it becomes excessive, as during the rewinding operation, when there might be excessive pressure produced under the speed at which the drive-shaft would then be turned.

As will be seen from the foregoing description, the simplicity and cheapness of the construction constituting my improvement adapts it to be installed in households, forges, and the like in which the use of other motor mechanism is not feasible, either because of

the expensiveness or of lack of the medium 50 for driving it.

What I claim as new, and desire to secure by Letters Patent, is—

1. An air-compressor comprising, in combination, a pressure-storage chamber provided with a valved pressure-inlet opening and a valved pressure-outlet opening, a bellows mounted immediately upon a wall of said chamber to constitute it one of the bellows-walls, said bellows covering said inlet-opening, and being provided with a valved air-inlet opening, a handle-equipped rotatable drive-shaft, a gear loosely mounted thereon and carrying a pallet, a ratchet-wheel on said shaft engaged by said pallet, a fixed gear and a windlass on said shaft, weighted-pulley mechanism having a cable connection with the windlass for operating the drive-shaft, a driven shaft, a fast gear near one end of said driven shaft meshing with the loose gear on said drive-shaft, a loose gear on said driven shaft carrying a pallet, a ratchet-wheel on the driven shaft engaged by the last-named pallet, a fast gear on the opposite end of the driven shaft, a gear operated by said last-named gear and carrying a pitman, and a link connecting said pitman with said bellows, for the purpose set forth.

2. An air-compressor comprising, in combination, a pressure-storage chamber provided with valved pressure-inlet openings and valved pressure-discharge openings, bellows mounted immediately upon the walls of said chamber each to constitute it one of the bellows-walls, each of said bellows covering an inlet-opening and being provided with a valved air-inlet opening, a handle-equipped rotatable shaft having a gear connection with each of said bellows for operating them, and weight-and-pulley mechanism connected with said shaft for actuating the bellows by the gravity of the weight, substantially as and for the purpose set forth.

HENRY H. HERRMANN.

In presence of—

J. H. LANDES,
A. U. THORIEN.
